UNITED STATES PATENT OFFICE

GEORGE A. SEELY, OF EMMETSBURG, IOWA, ASSIGNOR OF ONE-HALF TO
JOHN H. GODDEN, OF SAME PLACE.

TABLE-LEVELER.

SPECIFICATION forming part of Letters Patent No. 640,960, dated January 9, 1900.

Application filed April 17, 1898. Serial No. 713,382. (No model.)

To all whom it may concern:

Be it known that I, GEORGE A. SEELY, a citizen of the United States, residing at Emmetsburg, in the county of Palo Alto and State of Iowa, have invented certain new and useful Improvements in Table-Levelers; and I do hereby declare the following to be a full, clear, and exact description of the invention, such as will enable others skilled in the art to which it appertains to make and use the same.

This invention relates to table levelers or jacks for elevating and lowering the legs of billiard and like tables required to be kept in a horizontal position.

The purpose of the invention is to secure ease of adjustment, to have the leveler in condition for instant use at all times, and to prevent any accidental movement of the parts when adjusted to the required position.

The device consists of a base, a threaded stem rising from the base and adapted to enter an opening in the table-leg, a fixed follow-plate slidable upon the threaded stem, a plate having screw-thread connection with the said threaded stem, and an operating-handle integral with the threaded plate and adapted to be grasped when it is required to turn the threaded plate upon the threaded stem to secure an adjustment of the leg or part to which the device may be applied.

The invention further consists of the novel structural features set forth in detail in the following description and illustrated in the accompanying drawings, in which like parts are designated in all the views and referred to in the description by similar reference-numerals.

Figure 1 is a vertical section of the leveler, showing it applied to a table-leg. Fig. 2 is a plan view of the follow-plate. Fig. 3 is a perspective view of the screw or adjusting plate. Fig. 4 is a perspective view of the base and threaded stem.

The base 1 may be of any formation and as shown is a flat disk having openings 2 near its outer edge to receive screws, nails, or like fastenings when it is required to secure the

leveler permanently to the floor or like supporting structure. The threaded stem 3 rises 50 centrally from the base and may be formed therewith or fitted thereto. This stem 3 enters the opening 4, formed in the lower end of the table-leg 5.

The follow-plate 6 is of circular form and 55 has a central perforation 7 of a size to receive the stem 3 and admit of the plate sliding freely up and down thereon.

The circular adjusting-plate 8 has its central opening 9 internally threaded to act in 60 conjunction with the threads of the stem 3, so as to move up or down thereon when turned and effect a vertical adjustment of the table-leg. A handle 10 is formed integral with the plate 8 and projects straight out therefrom a 65 sufficient distance to afford ample leverage and enable a firm grip being obtained when it is required to rotate the plate 8 to adjust the part resting on the follow-plate 6.

Inasmuch as the leveler is designed for general use in connection with game tables, apparatus, and the like, it is to be understood that changes in the form, proportion, and minor details of construction may be resorted to without departing from the spirit of the 75 invention.

Having thus described the invention, what is claimed as new is—

A table-leveler, comprising a base having a centrally-disposed threaded stem integral 80 therewith and adapted to enter an opening in the table-leg or the like, a follow-plate having a central opening sufficiently large to receive the threaded stem and freely slidable thereon and bearing against the lower end of 85 the table-leg, and an adjusting-plate having screw-thread connection with the aforesaid stem and supporting the follow-plate and having an integral offstanding operating-handle, substantially as described. 90

In testimony whereof I affix my signature in presence of two witnesses.

GEORGE A. SEELY. [L. S.]
